UNITED STATES PATENT OFFICE.

GEORGE F. NOLTE, OF EVANSVILLE, INDIANA.

DESIGN FOR A TEA-SHELF.

No. 38,347.

Specification for Design.

Patented Dec. 11, 1906.

Application filed October 1, 1906. Serial No. 337,025. Term of patent 7 years.

To all whom it may concern:

Be it known that I, GEORGE F. NOLTE, a citizen of the United States, residing at Evansville, in the county of Vanderburg and State of Indiana, have invented a new, original, and ornamental Design for Tea-Shelves for Stoves or Ranges, of which the following is a specification, reference being had to the accompanying drawing, forming a part hereof.

The figure is a face view of a tea-shelf for stoves or ranges, showing my new design.

I claim—

The ornamental design for a tea-shelf for stoves or ranges as shown.

GEORGE F. NOLTE.
